Primary Examiner — Martie K Holtje(74) Attorney, Agent, or Firm — Belles Katz LLC(57) CLAIM

I claim the ornamental design for a yogurt maker, as shown and described.

DESCRIPTION

FIG. 1 is a front top perspective view of a yogurt maker showing my new design.

FIG. 2 is a rear bottom perspective view of the yogurt maker of FIG. 1.

FIG. 3 is a front view of the yogurt maker of FIG. 1.

FIG. 4 is a rear view of the yogurt maker of FIG. 1.

FIG. 5 is a right-side view of the yogurt maker of FIG. 1, the left-side view being a mirror image thereof.

FIG. 6 is a top view of the yogurt maker of FIG. 1; and, FIG. 7 is a bottom view of the yogurt maker of FIG. 1.

The broken lines formed by linear segments of equal length in the figures are provided for environment only and form no part of the claimed design.
